UNITED STATES PATENT OFFICE

HARRY H. WHEATLEY, OF PITTSBURGH, PENNSYLVANIA

STRINGED MUSICAL INSTRUMENT

Application filed April 4, 1929. Serial No. 352,430.

This invention relates to improvements in musical instruments, and more particularly to stringed instruments of the class characterized as banjos and similar instruments.

5 Present banjo constructions produce a metallic ring which is objectionable, and are provided with skin heads which are subject to change of temperature and humidity, which changes produce detrimental effects 10 on the tone of the instrument.

It is a prime object of this invention to provide a stringed musical instrument of the character stated including an air column disposed within the head of the instrument, said 15 column terminating in an expanded opening preferably within the front of said head, whereby the notes of the instrument are amplified and qualified to produce a strengthened and improved tone with a minimum of 20 playing effort.

It is a further object of my invention to provide a construction to transmit the sound vibrations of the instrument from the strings thereof through a diaphragm to the air column, wherein they are amplified and qualified to produce an improved tone.

Other and further objects are, to provide an instrument which will be free from disturbances due to changes of temperature and 30 humidity; an instrument which may be played with less effort than present constructions; and one which is economical in construction.

My invention may be more readily understood by a reference to the specification taken in connection with the accompanying drawings, wherein:

Fig. 1 is a front view of a stringed instrument embodying my invention;

40 Fig. 2, a sectional view on the line II—II of Fig. 1;

Fig. 3, a fragmentary sectional view on the line III—III of Fig. 1;

Fig. 4, an enlarged sectional view on the 45 line IV—IV of Fig. 1, particularly showing the bridge mounting;

Fig. 5, a sectional view taken on the line V—V of Fig. 1, particularly showing the connection of the diaphragm with the air column;

Fig. 6, a sectional view similar to Fig. 2, showing a modified form of air column;

Fig. 7, a perspective view, showing locking means applied to the bridge; and

Fig. 8, a perspective view of the locking means.

Referring to the drawings, 5 designates the head of the instrument, preferably cylindrical in construction and provided with a neck 6. Strings 7 of the usual number are secured 60 to the head 5, as at 8, pass over a bridge 9, and engage tightening pegs (not shown) in the outer end of the neck 6.

The bridge 9 is provided with the usual notches *a* for retaining the strings, and is 65 mounted on a cross member 10 having spaced-apart depending knife edges 11 thereon. Said knife edges engage a V-slot 12 of a hardened metallic member 13 secured in the face of a tail piece 5*a* integral with the head 5. 70

An arm 14, secured at one end to the bridge, is provided, which arm projects downwardly from the bridge 9 through an enlarged opening 15 of said tail piece; it is bent at its lower end and centrally engages a circular 75 diaphragm 16. The diaphragm 16 may be constructed of thin metal, fiber or mica, or any other suitable material to respond to the vibrations of the strings 7, and is secured peripherally to a hollow sounding box or casing 80 17 positioned within the head 5. The rear wall of the sound-box is formed with a central opening 18 adapted to communicate with the conduit, generally designated A.

The depth of the head 5 is sufficient to accommodate the circuitous conduit A. Said conduit affords a comparatively long air passage or column within the head of the instrument having a definite predetermined ratio of expansion. As shown in Fig. 1, the column 85 extends from the opening 18 of the sound-box 17, outwardly from said sound-box and downwardly toward the back of the head 5, until one of the walls *b* of the conduit merges into the cylindrical wall 19 of the head. The 90 opposite wall *c* terminates short of the wall 19 in an arcuate wall 20, the latter continuing around the enclosure of the head 5 at an increasing distance from the wall 19. In addition to the walls mentioned, the conduit con- 95 100

stituting the air column is formed by top *d* and the back 21 of the head 5, said top being disposed at an increasing distance from the back 21.

- 5 The air column terminates in a bell-shaped chamber B having an opening in the plane of the front of the head 5. This opened-top chamber is formed by a curved wall 22 having an opening 23 in communication with air column A. The length of said air column is such that its natural frequency shall be lower than the lowest note that can be played on the instrument. This is to avoid excessive strengthening of any note in the range of the instrument. This length may be determined by application of the laws governing sound vibrations in tubes closed at one end. Accordingly, the column will have a natural period of vibration low enough to allow it to respond equally to all notes within the range of the instrument.

For example, assuming the lowest note to be struck on the instrument is C below middle C, which note has a wave length of 106 inches. In a tube closed at one end, or a stopped tube, the length thereof should be equal to one-fourth the wave length of the fundamental tone, or in the case of C below middle C, 26.5 inches. Hence, the air column 30 will be of sufficient length to respond to C below middle C and all notes of higher frequency.

When a note is struck on the strings of the instrument, the vibrations set up are imparted 35 to the diaphragm by means of the bridge 9, cross-member 10, and depending arm 14. The vibrations are then transmitted through the air column A wherein they are amplified and equalized, emerging from the opening B in 40 a full, true tone.

In the form of Figs. 1 to 5 inclusive, I have shown the air column A rectangular in cross-section. Such a construction may be effected by laminated sections glued together.

45 However, as in Fig. 6, the air column A' may be constructed circular in cross-section, and fabricated of pressed fibre sections or the like. It is therefore understood that my invention is not to be limited to an air column 50 of specific cross-section.

It will be noted that this construction concentrates all the sound waves at the front of the head of the instrument and that this amplified tone or volume is directed outwardly and away from the instrument without interruption.

Obviously, the bridge 9 being adapted to oscillate on knife edges 11, is very sensitive and must be protected when the instrument 60 is not in use. Accordingly, I provide a U-shaped member 24, the sides of which are wedge-shaped and may be inserted between the bridge 9 and tail piece 5a of the head 5 to prevent oscillation of the bridge and dia- 65 phragm.

Various changes are contemplated, provided they fall within the scope of the appended claims.

I claim:

1. In a stringed musical instrument of the character specified, a hollow head having a sound conduit located entirely therein and open at the front of the head and of sufficient length to allow said column to respond equally to all notes within the range of the instrument, a sound box within the head connected with the conduit, and a string bridge on the head operatively connected to the sound box.

2. In a stringed musical instrument of the character specified, a hollow head having a circuitous sound conduit disposed entirely therein, and having its discharge end in the form of a bell-shaped chamber open in the plane of the front of the head to throw the sound outwardly therefrom.

3. A stringed musical instrument having a hollow head, a diaphragm positioned within the head to receive vibrations from the strings, means providing a sound conduit within the head and in communication with said diaphragm and adapted to receive the vibrations therefrom, said head having an open chamber disposed at the front thereof and from which the sound is directed without interruption.

4. A stringed musical instrument having a head, a sound box within the head, a bridge for the strings operatively connected to the sound box, said head having a sound conduit leading from the sound box and then extending around the same and opening at the front face of the head.

5. A stringed musical instrument having a head, a sound box within the head, said head having a sound conduit extending around the same and opening at the front face of the head, a tail piece on the head at said face extending over the outlet of said conduit, a string bridge on said tail piece, said conduit leading from the sound box, and an operative connection between the bridge and sound box.

6. A stringed musical instrument having a head, a sound box within the head, a bridge for the strings operatively connected to the sound box, said head having a sound conduit therein leading from the sound box and then extending around the same and opening at the front face of the head, portions of the walls forming said head also forming portions of the walls of said conduit.

7. A stringed musical instrument having a relatively flat cylindrical head, a neck extending from the head, a sound box in said head substantially in line with said neck, said head having a sound conduit therein leading from the sound box and progressively increasing in cross-sectional area in a direction away from the same, said conduit extending completely around the head and opening at

the front face thereof, a tail piece on the head extending over said outlet, a string bridge on said tail piece and adjacent said sound box, and an operative connection from the bridge to said sound box.

8. The subject matter of claim 7 wherein said bridge is fulcrumed on said tail piece, and wherein said connection comprises an arm extending loosely through the tail piece.

10 In testimony whereof I affix my signature.
HARRY H. WHEATLEY.
